US0D1008611S

(12) **United States Design Patent** (10) Patent No.: **US D1,008,611 S**
(45) Date of Patent: ** Dec. 26, 2023

(54) **FOOTWEAR**

(71) Applicant: **Mountain Origins Design LLC**,
Jackson, WY (US)

(72) Inventors: **Kurtis Tamotsu Sakai**, Santa Barbara,
CA (US); **Stephen Sullivan**, Wilson,
WY (US); **Kelly Hill Shuptrine**,
Jackson, WY (US)

(73) Assignee: **Mountain Origins Design LLC**,
Jackson, WY (US)

(**) Term: **15 Years**

(21) Appl. No.: **29/831,914**

(22) Filed: **Mar. 23, 2022**

(51) LOC (14) Cl. **02-04**

(52) U.S. Cl.

USPC **D2/910**

(58) **Field of Classification Search**

USPC D2/896-900, 907, 909-912, 919, 923,
D2/947-957, 960, 961, 969, 970, 972,
D2/977

CPC . A43B 3/10; A43B 5/00-18; A43B 13/00-14;
A43B 23/00

See application file for complete search history.

(57) **CLAIM**

The ornamental design for footwear, as shown and described.

DESCRIPTION

FIG. 1 is a perspective view of a novel footwear design.
FIG. 2 is a front view of the novel footwear design in FIG. 1.

FIG. 3 is a rear view of the novel footwear design in FIG. 1.

FIG. 4 is a left side view of the novel footwear design in FIG. 1.

FIG. 5 is a right side view of the novel footwear design in FIG. 1.

FIG. 6 is a top view of the novel footwear design in FIG. 1; and,

FIG. 7 is a bottom view of the novel footwear design in FIG. 1.

The broken lines are shown for illustration purposes only and form no part of the claimed design.

1 Claim, 5 Drawing Sheets
